UNITED STATES PATENT OFFICE.

JOSEPH A. GROEBLI, OF NEW YORK, N. Y., ASSIGNOR TO THE KURSHEEDT MANUFACTURING COMPANY, OF NEW YORK, N. Y., A CORPORATION OF NEW YORK.

STOP MECHANISM FOR EMBROIDERING-MACHINES.

No. 902,815.

Specification of Letters Patent.

Patented Nov. 3, 1908.

Application filed August 5, 1903. Serial No. 168,278.

To all whom it may concern:

Be it known that I, JOSEPH A. GROEBLI, a citizen of the United States, residing in the borough of Manhattan, city, county, and State of New York, have invented certain new and useful Improvements in Stop Mechanism for Embroidering-Machines, of which the following is a specification.

My invention relates to stop mechanism for embroidering machines and has for its object to produce a mechanism in which, if the embroidering or other machine should by any chance, initiate on the machine the operation of individual functioning mechanism the operations of which would be liable to interfere with each other when in action simultaneously, that the machine will be automatically stopped so as to prevent such interference and breakage.

My invention will be described with particular reference to a jacquard mechanism for controlling embroidering machines although it will be understood that I do not thereby mean to limit myself to the mechanism shown nor to the application of the mechanism to embroidering machines.

The present embodiment of my invention is additional to and forms part of a jacquard mechanism shown and described in U. S. Letters Patent No. 528632, granted to the Kursheedt Manufacturing Co., Nov. 6th, 1894, as my assignee. In this patent I have shown a jacquard mechanism for moving the fabric frame on an embroidering machine.

At subsequent dates, I patented a series of machines by which the operation of mechanisms executing special functions in the operation of embroidering machines could be initiated from the jacquard. For instance, in U. S. Letters Patent No. 556143, dated March 10th, 1896, I have shown means for perforating a fabric stretched upon the tambour frame of an embroidering machine, the said means being initiated and controlled from the jacquard. In U. S. Letters Patent No. 556144, I have shown means for adjusting the thread tension of an embroidering machine, which means is also initiated and controlled from the jacquard. In U. S. Letters Patent No. 556145, dated March 10th 1896, I have shown means for connecting the embroidering mechanism to and disconnecting it from its operating mechanism, which means is also initiated and controlled from the jacquard. In U. S. Letters Patent No.

593208, dated Nov. 9th, 1897, I have shown means for disconnecting the embroidering machine operating mechanism from its driving mechanism so that operations other than the needle stitching operations can be effected during such stoppage, which apparatus is initiated and controlled from the jacquard. In U. S. Letters Patent No. 607848, dated July 26th, 1898, I have shown means for forming festoons or scallops in the embroidering operation, which means is initiated and controlled from the jacquard. In U. S. Letters Patent No. 618458, dated Jan. 31st, 1899, I have shown means whereby either a bore point or a stupfel is thrown into operation, which mechanism is initiated and controlled from the jacquard. There are other Letters Patent showing means for automatically controlling mechanism for executing other functions, which I have not herein recited. All of these mechanisms are termed by me special or extra function mechanisms and it is obvious that there are other functions which may be designated as special functions, including the means for affecting the control and movement of the fabric frame.

As before stated, the object of my invention is to prevent the initiating or setting in operation of different sets of mechanism in the machine which would interfere with each other. In the accompanying drawing, I have shown one apparatus for effecting such result and describe the same by way of example.

In the drawings:—Figure I is a plan view of the apparatus which may be considered as an addition to the jacquard mechanism shown in U. S. Letters Patent No. 528632, dated Nov. 6th, 1894, and herein referred to, and is operative in the present instance to set a stop-motion in action to stop the jacquard and consequently stop the embroidering machine, Fig. II is an enlarged detail view of the stopping mechanism including the means connected to the special function mechanism for throwing the stop-motion mechanism into action which means I shall hereinafter term detector bars, Fig. III is a section on the line III—III of Fig. II, Fig. IV is a plan view similar to Fig. I showing certain detector bars omitted and the parts in a different position, Fig. V is an end view of some of the parts shown in Fig. IV, Fig. VI is a similar view showing the parts in a

different position, Fig. VII is a plan view similar to Fig. I showing certain detector bars and omitting others, Fig. VIII is an end view showing the parts in a certain position, 5 Fig. IX is a similar view of the same parts showing them in a different position.

In the drawings a^{23} indicates a rod which runs to the stop-motion mechanism of the jacquard. That is to say to the tail of the 10 latch 42 shown in Fig. I of U. S. Letters Patent No. 607234, to Groebli, dated July 12, 1898. It corresponds in function to the rod a^{23} shown in said figure. This rod is provided with an adjustable collar b , against 15 which an abutment c , on the stop lever d , is adapted to rest. This stop lever d , is carried upon a suitable shaft e , and is provided with a cam face f . (Figs. II and III.) In Fig. 20 III the dotted line position of the lever is the normal position, the full line position being the abnormal or stop position.

Sliding in a suitable frame g , supported by the frame work of the machine are detector bars Nos. 1, 2, 3, 4, 5, 6. These detector bars 25 are connected to mechanism for initiating and controlling certain special functions; for instance, detector bar No. 1 is connected to the scallop attachment, No. 2 to the shuttle changing mechanism, No. 3 to the mechanism 30 for disconnecting the embroidering machine when extra functions are to be performed, (for instance, such as boring) No. 4 is connected to the mechanism for effecting the adjustment of the bore points, No. 5 is 35 connected to the stupfel attachment, and No. 6 is connected to the bore point attachment.

I have shown diagrammatically in Figs. 40 IV to IX the directly acting means whereby the lifting of the detector bars is effected. Each of the special function mechanisms is provided with a suitable lifter for lifting the detector bars belonging to the mechanism which would interfere with the mechanism 45 actuating that particular lifter. For instance, in Figs. IV, V and VI, I have shown a hub K , provided with a cam i , the hub K of the three armed lever shown in Fig. 7 of U. S. Letters Patent No. 593208, to Groebli, 50 dated Nov. 9, 1897. This cam i , on hub K , operates upon a lifter j , pivoted at k , which lifter is adapted to raise detector bars Nos. 1 and 2, which detector bars are connected to the scallop attachment and the shuttle 55 changing attachment. The cam i , also operates upon a lifter l pivoted at m , and adapted to lift detector bars Nos. 5 and 6, which represent the stupfel attachment and the bore attachment.

60 In Fig. V the parts are shown in the positions which they assume when the embroidering machine is disconnected and in Fig. VI the parts are shown as in the position they assume when the embroidering machine is 65 connected. The member K in the present

case is the same member similarly lettered in Patent No. 593208 referred to, and it is the lever carrying member which is rocked to set a part of the machine into action. Fig. V shows how the cam i , is positioned when the member K throws the embroidering mechanism out of action while Fig. VI shows its position when the member K in this case, and in the patent referred to, moves the levers to throw the embroidering mechanism into action. 70

Referring for the present to the position shown in Fig. V, the detector bars Nos. 1 and 2 being in their elevated position, if the function represented by either were to go into effect that bar would be given a forward movement thereby swinging the lever d , on its pivot or shaft and stopping the machine. The same is true of the position shown in Fig. VI wherein the embroidering machine is 85 disconnected and the stupfel and bore attachment detector bars are in position to effect the stopping of the machine.

In Figs. VII, VIII and IX, I have shown the details of the detector bars and their ap- 90 purtenant mechanism coöperating with the stupfel and bore attachment mechanisms. In these figures the detector bars Nos. 3, 4, and 5 are alone involved, these being, respectively, the embroidering machine disconnecting mechanism, the adjustment of the bore point and the stupfel attachment. In these figures, 12 indicates a suitable movable part of the machine connected to the stupfel apparatus. This part 12 in the present instance, is the lower end of the rack or setting bar 12 of Patent No. 717843, to Groebli, dated Jan. 6, 1903. The part 12 acts upon the cam p , carried upon an arm q , pivoted at r , and provided with a lifter s , 105 which operates upon detector bar No. 3, which is connected to the mechanism for disconnecting the embroidering machine. In Fig. VIII, the stupfel is out of operation and in Fig. IX it is in operation, its lifter holding 110 detector bar No. 3 in its elevated position so that if the embroidering machine should by any chance be connected up, such for instance, as by a tear in the jacquard card or paper, the machine will be immediately 115 stopped. The bore attachment mechanism and its coöperating mechanism swing the arm u , having a pin u^1 which acts on the cam w to which the lifter X pivoted at r is connected. The lifter X is adapted to lift the detector bars Nos. 3, 4, and 5 so that if any of the 120 functions represented by any of these three bars is initiated while the bore point attachment is in action the machine will be stopped. Fig. VIII shows the position assumed by the parts when the bore point attachment is in action and Fig. IX shows the position of the parts when the bore point attachment is out of action. 125

The lever u is a part of the bore mechanism 130

and when it rocks back and forth on its fulcrum *v* in conjunction with the setting of the bore mechanism into and out of action, it rocks the member *w* to operate the lifter *X*.
 5 This lever *u*, or any equivalent device may be operated in any suitable way so that it produces an action on the desired lifter. In the particular construction to which this lever *u* belongs, the pin *t*, is forced by the jacquard into engagement with the lever *u* and a continuously oscillating lever, (not shown) whereby the lever *u* is moved to either of its positions shown in Figs. VIII and IX.

The machine under consideration operates as follows: If the lifter *k* corresponding to any function mechanism is actuated to start to position said mechanism for action, coupled for action or in anywise initiate the function thereby represented the detector bar corresponding to such function is thrust forward into the position shown at 3 in Fig. II. This is before the said mechanism is coupled up or otherwise put in position or condition for action. When the mechanism starts to operate 25 it will lift up the bar or bars of mechanism which conflict with it in action. Should any of these mechanisms be in action, their bars will be in their forward (full line) positions and raising its detector bar will cause the same to traverse the face of the cam *d* and swing the arm to stop the machine. If the interfering functioning mechanism is not in action its bar will in its upward movement clear the lever *d*. But should the interfering 30 mechanism be put in action while the first mentioned functioning mechanism is in action it will be thrust forward and, striking the lever *d*, stop the machine. As soon as the operation of the operating functioning mechanism ceases the bars will be restored to position by a reverse movement. Should two interfering mechanisms be set in operation about simultaneously each will thrust its detector bar forward (full line position) 40 but on the lower level, and raise the bar of the other interfering mechanism. Thus both bars will rise together and one or both stop the machine by traveling over the face *f* of the arm *d*.

45 In the claims I have employed the terms interfere, interfering, etc. I do not use these terms merely in the sense of indicating that the mechanisms are liable to strike each other in their movement but desire the terms to be used also in the broad sense of interference in the harmonious production of the finished product, to wit, the embroidery, where there is no actual, physical or mechanical interference.

50 Having described my invention, what I claim is:

55 1. In an embroidering machine, the combination of an embroidering apparatus including a jacquard mechanism and a plurality of individual mechanisms controlled

by said jacquard mechanism and operating to secure different functions and which mechanisms are liable to interfere with each other if in operation at the same time, with means for stopping said embroidering apparatus 70 when two or more individual mechanisms are liable to interfere.

2. In an embroidering mechanism the combination of an embroidering means, a jacquard device with a plurality of separately operating mechanisms executing different functions which mechanisms are liable to interfere with each other if in operation at the same time and which mechanisms are located to operate at the same point and initiated from the jacquard device and means for preventing interference between the said mechanisms. 75

3. In an embroidering mechanism, the combination of a series of individual mechanisms for effecting different functions, parts of which mechanisms are liable to interfere with other individual mechanisms should both individual mechanisms be operated at the same time, a stop motion mechanism and 80 automatic means for operating the stop-motion mechanism when any two of such mechanisms which are liable to interfere operate at the same time. 85

4. The combination in an embroidering mechanism of a series of special function mechanisms adapted to execute different functions and so located as to partly occupy the same space when in action, a stop-motion mechanism and means connected to the 100 special function mechanisms for actuating the stop-motion mechanism and means connected to the various special function mechanisms for positioning the stop-motion actuating mechanism of the special function 105 mechanism which will interfere therewith.

5. In an embroidering mechanism the combination of pattern mechanism, of pattern mechanism initiated special function mechanisms, stop motion mechanism stopping the machine through the pattern mechanism and means for rendering the said stop motion mechanism active when interference between two special function mechanisms is about to occur. 110

6. In an embroidering mechanism the combination of pattern mechanism, of pattern mechanism initiated special function mechanisms having or operating parts so located as to be liable to interfere one with the other if simultaneously operated, a stop motion mechanism and connections between the special function mechanisms and the stop motion mechanism for actuating the stop motion mechanism upon the conjoint action 120 of two interfering mechanisms.

7. In an embroidering machine the combination of a series of special function mechanisms having or operating parts so located as to be liable to interfere one with the other 130

if simultaneously operated, pattern mechanism for initiating their operation, a stop motion mechanism and means for actuating the stop motion mechanism from the pattern mechanism upon the conjoint action of interfering functioning mechanisms.

8. In an embroidering machine the combination of a series of special function mechanisms having or operating parts so located as to be liable to interfere one with the other if simultaneously operated, a stop motion mechanism for the various special function mechanisms and means cooperating with the various special function mechanisms for effecting the operation of the stop motion

mechanism from the mechanism or mechanisms which are liable to interfere when in action simultaneously.

9. In an embroidering machine the combination of mechanisms for executing special functions so located as to be liable to interfere with each other when in operation, of operating means for the same liable to operate the same simultaneously and automatically acting means for preventing the simultaneous action of interfering mechanisms.
